UNITED STATES PATENT OFFICE.

CHARLES J. WITZEL, OF NEW YORK, N. Y.

WIRE MATTRESS.

No. 921,494.

Specification of Letters Patent.

Patented May 11, 1909.

Application filed March 12, 1909. Serial No. 482,919.

REISSUED

To all whom it may concern:

Be it known that I, CHARLES J. WITZEL, a citizen of the United States of America, residing in New York, in the borough of Brooklyn, county of Kings, and State of New York, have invented certain new and useful Improvements in Wire Mattresses, of which the following is a specification.

This invention relates to an improvement 10 in the spring and woven-wire mattresses, by which the horsehair or other mattresses that are supported on the same, are held in position thereon and prevented from shifting to one side or the other.

15 It is one of the objections to the metallic bedsteads in general use that the horsehair or other mattresses which are placed on the wire-mattresses are shifted on the same by the slightest touch from one side to the other, 20 so that a very unsightly appearance is given to the beds either when exhibited in the store or when in use.

The object of this invention is to obviate the shifting of the horsehair or other mattresses on the wire-mattresses by holding the same securely in position on the wire-mattress and prevent in a reliable manner the unsightly shifting of the horsehair mattress on the same; and for this purpose the invention 25 consists of a wire mattress which is provided at both sides with bent-up longitudinal guards which are reinforced by heavier strands along the side-edges of the wire-mattress and at the upper edges of the bent-up 30 guards, said bent-up guards being attached to bent-up lugs on the transverse end-straps of the wire-mattress, and the bent-up lugs connected by coiled springs with auxiliary lugs which are attached to the metallic cross- 35 bars at the ends of the wire mattress by 40 which the same is supported in the bedstead.

In the accompanying drawing, Figure 1 represents a perspective view of a metallic bedstead with my improved wire-mattress 45 placed in position in the same, Fig. 2 is a perspective view of one end of the wire mattress, drawn on a larger scale, and Fig. 3 is a vertical transverse section on line 3, 3, Fig. 2.

Similar characters of reference indicate corresponding parts in the figures of the drawing.

Referring to the drawing, *a* represents a woven-wire mattress of any approved construction. The longitudinal edges of the

woven-wire mattress *a* are reinforced by 55 thick strands *a*¹. Cross-straps *b* are attached to the opposite ends of the woven-wire mattress and connected in the usual manner by coiled springs *d* with the transverse angular head or foot-piece *e* of the mattress, by which 60 the latter is supported by the usual brackets *e*¹ on the side-rails of the metallic bedstead. The woven-wire mattress *a* is woven beyond 65 the reinforcing strands *a*¹ for a distance of approximately two inches, the edges being reinforced by additional strands *a*². Both longitudinal extensions or guards *a*² at the sides of the wire-mattress are bent up at right angles to the body of the mattress and attached to lugs *b*¹ that are bent up from 70 the cross-straps *b*. The bent-up lugs *b*¹ are connected by auxiliary coiled springs *d*¹ with auxiliary angular lugs *d*² which are attached to the angle-irons *e* at the head and foot of the wire-mattress, as shown in Fig. 2. The 75 auxiliary springs *d*² serve to keep the bent-up guards *a*² rigidly in taut position in the same manner as the coiled springs *d* keep the mainportion or web of the woven wire-mattress in tightly stretched position.

The bent-up guards *a*² with their reinforcing strands *a*³ keep the horsehair mattress in position when the same is placed on the woven-wire mattress and prevent the lateral shifting of the same; while the horsehair 80 mattress has some longitudinal play between the head and foot-pieces of the metallic bedstead, the lateral shifting of the horsehair mattress is prevented and the same held always in proper position between the side-guards. The unsightly and disagreeable 85 shifting of the horsehair mattress is thereby prevented. The longitudinal side-guards add but little to the expense of the woven wire-mattress, which is shipped in the same 90 manner as ordinary wire-mattresses, the tension-springs preventing the mattress and its side-guards from getting out of shape.

Having thus described my invention, I claim as new and desire to secure by Letters 95 Patent:

1. A woven-wire mattress provided with bent-up side-guards forming extensions of the body or web of the mattress, transverse end-straps applied to the woven-wire mattress and provided with bent-up lugs to which the side-guards are attached, auxiliary angular lugs attached to the angle irons 105

at the foot and head of the mattress, coil-springs between the transverse end-straps and angle irons, and coil-springs between the bent-up lugs of the end-straps and the auxiliary lugs of the angle-irons.

2. In a woven-wire mattress, the combination, with a woven-wire web having bent-up extensions or guards at the sides, of longitudinal strands for reinforcing the edges of the web and bent-up guards, transverse end-straps having bent-up lugs attached to opposite ends of the web and side-guards, angle-irons at the head and foot of the mattress, auxiliary lugs attached to said angle-irons, in line with the lugs of the transverse straps, coil-springs interposed between the transverse end-straps and angle-pieces, and auxil-

iary coil-springs between the bent-up lugs and auxiliary lugs.

3. A woven-wire mattress provided with reinforcing strands at both sides, bent-up side-guards forming extensions of the wire mattress also provided at their edges with reinforcing strands, and transverse end-straps provided with bent-up lugs to which the ends of the side-guards are attached.

In testimony that I claim the foregoing as my invention, I have signed my name in presence of two subscribing witnesses:

CHARLES J. WITZEL.
